UNITED STATES PATENT OFFICE

RUSSELL K. HARSH, OF DALLAS, TEXAS

DESIGN FOR A GAME BOARD OR ANALOGOUS ARTICLE

Application filed April 30, 1932. Serial No. 43,673. Term of patent 3½ years.

To all whom it may concern:

Be it known that I, RUSSELL K. HARSH, a citizen of the United States, residing at Dallas, in the county of Dallas and State of Texas, have invented a new, original, and ornamental Design for a Game Board or Analogous Article, of which the following is a specification, reference being had to the accompanying drawing, forming a part thereof.

I claim:

The ornamental design for a game board or analogous article as shown.

RUSSELL K. HARSH.
